LAMP DEVICE
 Wilbur C. Wade, 16572 SE. Mill St., Portland, Oreg.
 Filed Dec. 18, 1961, Ser. No. 160,160
 1 Claim. (Cl. 40—77)

This invention relates to a type of lamp device, and more particularly to a novel lamp device that includes adjustable mechanism for dispensing information. In a particular embodiment of the invention, a lamp device is contemplated that may be used by piano and organ players, and the like. Information dispensed by the adjustable mechanism may then relate to chord structure, and serve as an aid to the player as he performs.

A general object of the invention, therefore, is to provide a novel type of lamp device, that includes novel adjustable mechanism for dispensing information.

A related object is to provide such a device, with an information dispensing mechanism constructed in a novel manner whereby part of the light emitted from the usual lamp bulb in the device is used to illuminate an indicator body in the mechanism having marked thereon the information to be dispensed. Thus, the indicator body may be read easily in darkened rooms.

A further object is to provide a lamp device, with illuminated mechanism for dispensing information, where the mechanism is constructed so as fully to utilize available light.

Related objects are to provide a lamp device of the above general description that is easy to manipulate in order to obtain the information desired therefrom; a lamp device that is readily adjusted to a position where direct light is shielded from the person using the lamp device; and a lamp device that is simply and economically constructed, and thus producable at relatively low unit cost.

These and other objects and advantages are attained by the invention, and the same is described hereinbelow in conjunction with the accompanying drawings, wherein:

FIG. 1 is a side elevation of a lamp device constructed according to one embodiment of this invention, and with portions of the device broken away to illustrate details of interior construction;

FIG. 2 is a front elevation of portions of the lamp device illustrated in FIG. 1;

FIG. 3 is a cross-sectional view, on a somewhat enlarged scale and taken generally along the line 3—3 in FIG. 1, illustrating details of an indicator body that is part of adjustable information dispensing mechanism in the lamp device; and

FIG. 4 illustrates, also on a somewhat enlarged scale, portions of a cylindrical shade in the device and how information may be read in viewing the indicator body through apertures provided in the shade.

Referring now to the drawings, and first of all in particular to FIGS. 1 and 2, the lamp device shown comprises generally an upright standard or support, indicated at 10, having an upper portion 10a bent over at an angle, and a substantially vertical lower portion 10b. A base 12 is provided at the bottom end of lower portion 10b, and such serves as a support for the lamp device as a whole. Mounted on the other end of standard 10 is hood structure indicated generally at 14.

Interconnecting base 12 and standard 10 is a socket assembly 16 pivotally connected at 18 to base 12 so as to accommodate swinging of the standard about a horizontal axis, and thus swinging of the standard to various inclined positions. The base of the standard is rotatable within assembly 16 about a vertical axis in FIG. 1. Such movement afforded the base of the standard

2

accommodates positioning of hood structure 14 in various positions to the front, rear, and sides of base 12.

Hood structure 14 is connected to the opposite end of the standard through a socket assembly 20 similar to socket assembly 16 just discussed. Thus, at 22 there is indicated a pivot connection pivotally connecting structure 14 to standard 10 with structure 14 swingable about a horizontal axis in FIG. 1. Structure 14 is rotatable relative to the top end of standard 10 about an axis extending longitudinally of portion 10a. The connection of hood structure 14 with standard 10 is such as to enable the hood structure to be tilted over at either end, or swung up and down.

Considering now the construction of hood structure 14, and referring now to FIGS. 1, 2, and 3, structure 14 comprises an elongated and substantially cylindrical shade element 24 connected midway between its ends to socket assembly 20 through lug 25. In the embodiment illustrated, each end of shade member 24 is closed off by a cup member secured in a suitable manner to the shade member, such as cup or closure member 26 closing off the left end of the shade element in FIG. 3. Shade element 24 has a bounding edge 24a, and extends from this edge over approximately a 270° angle to another edge 24b. Edges 24a, 24b define an elongated opening extending along one side of the shade element, and the shade element extends substantially without interruption between edges 24a, 24b over the other side of the shade element.

An adjustable information dispensing mechanism in the lamp device comprises a rotatable indicator body or cylinder 30, journaled within the hood structure adjacent one end thereof. The indicator cylinder is rotatable about its longitudinal axis, and such axis coincides with the longitudinal axis of shade element 24.

In the embodiment illustrated, the indicator cylinder comprises end members or spiders 32, 33, spaced along the length of the indicator cylinder, and secured to the ends of a shaft 34. Spider 32 at the right end of the indicator cylinder in FIG. 3 is secured directly to shaft 34 by a screw 36. Spider 33 at the left end of the indicator cylinder in FIG. 3 has a cover cap 38 joined thereto, and a nut 40 and screw 42 secure the cover cap and spider together with a washer 44 therebetween. The cover cap and spider 33 are secured to shaft 34 by screwing screw 42 into an accommodating threaded bore in the end of shaft 34. At 46 there is indicated a lock washer that holds nut 40 securely with the cover cap and spider 33 joined as one. Felt rings are indicated at 47.

Spiders 32, 33 have annular flange portions 48 that extend toward each other from opposite ends of the indicator cylinder. Fitted on the inside of these flanges and seated in grooves 50 is a section of material 52 that is pervious to light. Such section ordinarily might take the form of a light-colored, translucent plastic sheet. Informative markings are prepared on the surface of section 52. A portion of section 52 is shown in FIG. 4, and such markings are indicated at 54.

Mounted within hood structure 14 adjacent the end opposite indicator cylinder 30 is a lamp socket means 56, of conventional construction, for mounting a lamp bulb 58. A conductor 66 supplies electric current to socket means 56. Over the end of shade element 24 is a cover cap 60, that snugly encircles the outside of cup 26 closing off the end of the shade element. Lamp socket means 56 is secured in place by a nut 62 screwed onto an externally threaded portion 64 that is part of the lamp socket means and that extends through cup 26 and cap 60. Switch knob 65 is for turning the lamp on and off. Lamp bulb 58 within the hood structure is exposed by the opening de-

fined by edges 24a, 24b, and with the bulb energized, light shines out through this opening.

Spiders 32, 33 have apertures 68 therein that open to the interior of the indicator cylinder or body. For this reason, the interior of the indicator cylinder is lighted by light emitted from a lamp bulb in socket means 56. Light inside the indicator body shines through light-pervious section 52 thus to illuminate the informative markings on the section during use of the lamp device.

It should be noted that the opening along one side of the hood structure defined by edges 24a, 24b extends the entire length of the hood structure, and that a portion of light-pervious section 52 is exposed by the opening. Light shining through section 52 passes through the opening where the section is exposed. Thus, with a lamp bulb lighted, light is given off along the entire length of hood structure 14.

Apertures 70 are provided in shade element 24, and these are spaced away from edge 24b, in a direction extending from this edge around the sides of the shade element opposite the side containing the opening, to edge 24b. Three of such apertures are indicated, although various other numbers could be provided, if desired. On rotation of the indicator cylinder, selected ones of the informative markings on section 52 come into registry with the apertures, thus to become discernible to a person looking at the outside of shade element 24.

In a typical case, the lamp device may be intended to aid a piano or organ player, and the adjustable mechanism described used to dispense information relating to chord structure. Thus, as can be seen in FIG. 4, under the upper left aperture 70 labeled "CHORD NAME" there appears a letter "C" (marked on section 52) which designates a specific key. To the right of this aperture, is an aperture which is labeled "CHORDS MOST COMMONLY USED IN THIS KEY." Here letters "E7," "A7," "D7," "G7," "F," and "Fm" appear. These indicate chords that are commonly used in the key of C. The lower aperture may be used to indicate other chords used in the key of C, with certain musical effects produced. On rotation of the indicator cylinder, similar information in connection with other keys may be made to appear through the apertures 70.

In using the lamp device, the cover cap 38 at the left end of the hood structure constitutes a turn means enabling turning of the indicator cylinder within the hood structure. Adjustment of the indicator cylinder is easily made by holding structure 14 adjacent its other end with one hand, and with the other hand turning cover cap 38. Thus, an adjustment may be made, without touching central parts of structure 14, where one might be subjected to becoming burned.

Summarizing some of the novel features of the invention, light from the lamp bulb shines into the indicator cylinder from one end, and is used to light its interior and thus make markings on section 52 observable. Apertures 70 are located on a portion of the shade that may be viewed with the viewer's eyes shielded from direct light from the lamp bulb. Light shines through the opening in hood structure 14 along the entire length of the opening. Pivotal movement in the lamp standard 10 accommodates positioning of the hood structure easily to a position where apertures 70 are visible and the lamp bulb within the hood structure is shielded.

I claim:

In a lamp device
an elongated, substantially cylindrical shade having an opening extending along one side thereof,

a closure member joined to each end of the shade closing off the end,
an indicator cylinder concentrically disposed within the shade with an outer end of the cylinder adjacent one end of the shade and an inner end of the cylinder inwardly in the shade and intermediate its two ends,
lamp mounting means within the shade mounted on the closure member closing off the end of the shade opposite its said one end, for supporting a lamp, with such lamp positioned substantially axially centrally of the shade, between said inner end of the indicator cylinder and said opposite end of the shade,
said indicator cylinder comprising a light pervious section of material with markings thereon extending circumferentially about the cylinder, inner and outer end members upon which said material is mounted adjacent inner and outer ends of the cylinder, respectively, and a shaft extending along the axis of the indicator cylinder interconnecting the end members having an inner end terminating at the inner end member of the cylinder and an outer end adjacent said one end of the shade,
means mounting said cylinder only within said shade only through its outer end whereby the inner end of the cylinder is suspended by its outer end, said means including means journaling the outer end of said shaft in the closure member closing off said one end of the shade,
a cover cap concentric with said shade outwardly of the cover member closing off said one shade end, aligned axially with said shaft,
means connecting the cover cap and shaft whereby the cover cap when turned turns the shaft and with the shaft said cylinder,
a ring between the outer end of the cylinder and the closure member at said one end of the shade and between said closure member and the inside of said cover cap, providing friction tending to hold the cylinder from turning, and
an aperture in the shade element registerable with selected ones of the markings on the light pervious section,
said inner end member of the cylinder having means whereby light from a lamp passes therethrough and into the inside of the cylinder.
